FRANK H. FRISSELL, OF MIDDLETOWN, CONNECTICUT, ASSIGNOR TO THE RUSSELL MFG.
CO., OF MIDDLETOWN, CONNECTICUT, A CORPORATION.

MACHINE-GUN FEED-BELT.

1,260,890.

Specification of Letters Patent. Patented Mar. 26, 1918.

Application filed November 9, 1917. Serial No. 201,050.

To all whom it may concern:

Be it known that I, FRANK H. FRISSELL, a citizen of the United States, residing at Middletown, in the county of Middlesex and State of Connecticut, have invented a new and useful Improvement in Machine-Gun Feed-Belts; and I do hereby declare the following, when taken in connection with the accompanying drawings and the characters of reference marked thereon, to be a full, clear, and exact description of the same, and which said drawings constitute part of this application, and represent, in—

Figure 1 a broken plan view of a machine-gun feed belt constructed in accordance with my invention.

Fig. 2 an edge view thereof with a portion of its cartridge-receiving pockets open at their inner ends.

Fig. 3 a view in transverse section on the line 3—3 of Fig. 1, on a greatly enlarged scale.

My invention relates to an improved woven machine-gun feed belt, the object being to produce a simple, effective and durable belt constructed with particular reference to insuring the entrance of the pocket-opening needle of a belt-loading machine into the inner ends of its cartridge-receiving pockets to prepare the same for the insertion thereof into of the cartridges.

With these ends in view, my invention consists in a machine-gun feed belt characterized by having one or more strands of spring wire incorporated into its inner edges for normally maintaining the inner ends of its cartridge-receiving pockets sufficiently open for the reception of the pocket-opening needle of a belt-loading machine.

My invention further consists in certain details of construction as will be hereinafter described and pointed out in the claims.

In carrying out my invention as herein shown, I introduce, in the process of weaving the belt, whatever its specific character, a wire cable consisting of a plurality of strands 4 of spring wire inclosed in a braided envelop 5, into the complementary inner edges 6 of a woven feed belt having alternating cartridge-receiving and stay-receiving pockets 7 and 8, the former being adapted in size for the reception of standard cartridges which are not shown, and the latter being adapted in size for the reception of suitable belt-stays to prevent the belt from

collapsing edgewise. As herein shown, 1 employ loop-like belt-stays 10 made of wire the inner ends of which are bowed for the reception between them of eyelets 11 by means of which the stays are secured in 60 place at points along the inner edge of the belt. At intervals, the belt-stays 10 are replaced by special belt-stays 12 also made of wire and having their inner ends extended to form loop-like fenders 13 which project beyond the ends of the cartridge-bullets when the cartridges are in place in the cartridge-receiving pockets 7. These special belt-stays act not only as belt-stays, but also as fenders to prevent the bullets from being engaged 70 at their ends, endangering the displacement of the cartridges in the belt. I would have it understood, however, that I do not limit myself to belt-stays of any particular construction or mode of application, or even to 75 the employment of any belt-stays, since they have nothing to do with my present invention.

When my improved belt is initially woven, the inner ends of the cartridge-receiving 80 pockets 7 are substantially closed, as shown in the left hand portion of Fig. 2. However, prior to loading the belt for the first time, the inner ends of the cartridge-receiving pockets are manually opened, as shown 85 in the right hand portion of Fig. 2, whereby the wire cables incorporated into the edges of the belt, are sufficiently set outwardly in a regular series of oppositely located outward curves, to thereafter keep the inner ends of 90 the said pockets open enough to insure the entrance of the pocket-opening needle of a belt-loading machine, the said needle being used for preparing the pockets for the cartridges which are entered bullet-end fore- 95 most from the outer edge of the belt.

In the actual use of the belt for feeding the cartridges with which it is loaded, and in the handling of the belt for one purpose or another, the cartridge-receiving pockets 100 will become somewhat closed, but the embedded spring wires will normally hold them sufficiently open to insure the entrance of the pocket-opening needle, whereas it frequently happens in woven machine-gun feed 105 belts, that the cartridge-receiving pockets close to such an extent that the needle does not enter them, but passes above or below them, and so fails to prepare the pockets for the reception of the cartridges. It may be 110

explained in this connection, that the loading machines are constructed so that the pocket-opening needle enters the cartridge-receiving pockets from the inner edges of the belt and fully opens the pockets throughout the length thereof. Then, as the needle retires, a cartridge follows it very closely from the outer edge of the belt.

Preferably, and as herein shown, my invention is applied to belts having alternating cartridge-receiving and stay-receiving pockets, but is not so limited.

I claim:-

1. A woven machine-gun feed belt having cartridge-receiving pockets, the inner edges of the belt having incorporated in them, spring wires which maintain the inner ends of the said pockets normally open to insure

the proper entry of the pocket-opening needle of a belt-loading machine.

2. A woven machine-gun feed belt having spring wire cables incorporated at the time of weaving the belt into the edges thereof for normally maintaining the inner ends of the cartridge-receiving pockets of the belt sufficiently open to cause the entry into them of the pocket-opening needle of a belt-loading machine.

In testimony whereof, I have signed this specification in the presence of two subscribing witnesses.

FRANK H. FRISSELL.
